PROCESS FOR MAKING GYMNASIUM FLOORS FAST

Cecil Myron Curtis, Prairie City, Ill.

No Drawing. Application March 12, 1947,
Serial No. 734,233

1 Claim. (Cl. 117—104)

1 The present invention relates to an improved product and process for making gymnasium floors fast, and to the floor thus produced.

In playing athletic contests on an indoor playing field, such as a gymnasium floor, the players wear footwear having rubber or composition soles and heels in order to prevent marring the floor and to secure a better footing. However, after much use, such floors tend to become slippery, so that even rubber footwear provides a relatively insecure footing which retards the start in a quick run or other play involving fast action that requires a firm footing.

Heretofore it has been proposed to cover floors of gymnasiums with various compositions for the purpose of providing what is technically termed a "fast" floor. Such compositions have the disadvantage that they are expensive, require a relatively long drying time to lose their tackiness, or provide a coating which hardens and becomes rough and scratched, and which therefore has to be renewed by refinishng the floor. The renewal of such a coating is expensive, as the old coating, and possibly the varnish finish of the floor must be removed before a new coating can be applied. Such removal and reapplication of the coating, furthermore, requires more time than is available between successive uses of the floor, as for example, between halves of a basketball game, or even between afternoon and evening uses of the floor.

It is an object of the present invention to provide a composition for the treatment of varnished or unvarnished floors of gymnasiums or the like, which improves the traction to rubber or composition shoes and provides a fast floor.

A further object is the provision of a method of treating floors which improves the traction qualities thereof for rubber or composition footwear.

Another object is the provision of a fast floor for a gymnasium and upon which the coating can be readily and quickly renewed.

The present invention is based upon my discovery that an oil thinly spread upon a gymnasium floor improves the traction qualities of such a floor for rubber or composition footwear, and provides a fast floor. In view of the general property of oils to impart slipperiness to a surface, it was not to be expected that the traction qualities of a floor would be improved in this manner.

The specific oil used in carrying out my invention in any given instance, will depend to some extent upon the nature of the rubber with which

2 the shoes used by the contestants is shod. To obtain the desired traction qualities it is essential to use a thin coating or dew of discrete small particles of the oil on the floor, and therefore I prefer to apply the oil in the form of a diluted mixture, preferably applied as a fine mist or spray. The application of the oil in a thin or dispersed coating is assisted by diluting the oil with a suitable thinner or solvent, preferably one which is readily volatile and is non-toxic and non-inflammable, and spraying the diluted oil upon the floor in a thin layer. However, for applying the oil spray to a varnished floor, a solvent should be selected which does not have a softening effect upon the varnished surface. An excessively heavy application of oil is to be avoided as this produces a slippery floor. The amount of oil to be used conveniently may be determined by trying the floor after each application with rubber soled shoes until the desired traction is obtained. A coating averaging more than about one ten thousandth of an inch is to be avoided.

As examples of oils suitable for carrying out the present invention, I may mention the various commercial mineral oils, animal oils, fish oils or vegetable oils, such as corn or maize oil, cotton seed oil, peanut oil, soya bean oil, tung oil, linseed oil and castor oil, or other fatty oil. It will be observed that some of the above mentioned oils are drying oils, some are semi-drying, and some are classed as non-drying oils. In particular I prefer to employ the vegetable oils classed as non-drying oils, and of the non-drying oils, the preferred example is castor oil, as I have found this oil effective for a wider range and variety of rubber shod shoes. It will be understood that athletic shoes are shod with rubber or synthetic rubber compositions, and I have found that castor oil is effective for all the commercial rubber shod shoes of which I am aware.

Any suitable solvents or thinners may be employed with the oil, such as the commercial hydrocarbon solvents, alcohols, carbon tetrachloride, and the like, the latter solvent being preferred because of its high volatility, non-inflammability and relative absence of toxicity under the conditions of use.

The treatment of a gymnasium floor which has become slippery, according to the present invention, results in greatly increasing the traction qualities of the floor by increasing the adhesive properties of the rubber shod shoes worn in using the floor. The floor is ready for use immediately after treatment, although in some instances a

short time may be allowed for evaporation and dissipation of the solvent. I believe the reason for the improvement in traction qualities of the treated floor is due to the absorption of the oily dew by the rubber soles or heels of the footwear, the quantity of oil absorbed not being great enough to cause more than a slight softening of the exposed surface of the footwear.

As rapidly as the softened rubber wears away, the previously unexposed rubber picks up minute quantities of oil from the floor, so that always a slightly softened rubber surface is in contact with the floor. Probably also during use, the floor becomes thinly coated with a mixture of rubber and oil which presents a dry appearance, and this coating also acts as a friction producing coating, and being of a clear color, also enhances the beauty of the floor.

The invention will be described in detail in connection with the following example, given by way of illustrating the invention.

Example

A mixture is prepared from three parts by volume carbon tetrachloride and one part castor oil, commercial grade, which may be natural oil or blown. This mixture is sprayed upon a gymnasium floor, which may be a wood varnished or unvarnished floor, in a thin layer, using about one third to one half pint of the mixture to about four thousand square feet of floor, which produces a coating averaging about four millionths to six millionths of an inch in thickness. The floor now is ready for use, or if desired, a time interval may be allowed for evaporation of the carbon tetrachloride. When the floor is used by contestants wearing rubber shod gymnasium shoes, the traction of the floor is greatly increased over the untreated floor, the floor becoming what is technically called a fast floor. This property of the floor is retained for several hours' use, and can be renewed when required without first cleaning the floor.

During the course of use, some or all of the coating may be dissipated, especially in those parts of the floor which have been used most, so that it may become necessary to renew the coat before each period of use, or at intervals while the floor is in use. Because the floor is

ready for use immediately after the coat is applied, it is apparent that the coat may be applied during intermissions in the progress of a game. Furthermore, as the coating builds up, the floor acquires a wax-like finish, due to the accumulation of oil and rubber thereon and the polishing action that occurs in use, which enhances the beauty of the floor and assists in protecting the floor. Excessive accumulation of rubber on the floor can be removed readily by any of the usual floor cleaning methods, and the oil assists in making the rubber readily removable.

Various modifications of the invention may be made without departing from the spirit or scope thereof. The above example therefore is to be taken as illustrating rather than limiting the invention, unless otherwise indicated herein.

What I claim as my invention and desire to secure by United States Letters Patent is:

The process of making a wooden gymnasium floor fast to rubber shod shoes in action on the floor, which consists in spraying said floor, in the form of a fine mist with a solution consisting of a highly volatile, organic, non-toxic solvent in major amount and a non-drying vegetable oil in minor amount, sufficient to deposit, after volatilization of the solvent, a thin film, having an average thickness of less than one ten-thousandth of an inch of discrete oil particles, to afford softening of the soles and heels of shoes in action on the floor, and to prevent slippage while in use on the floor.

CECIL MYRON CURTIS.
